UNITED STATES PATENT OFFICE.

WILLIAM E. ELLIOTT, OF GRAND RAPIDS, MICHIGAN, ASSIGNOR TO AMERICAN BUTTON & FASTENER CO., OF AUGUSTA, MAINE, A CORPORATION OF MAINE.

MACHINE FOR MOUNTING ARTICLES.

Application filed August 1, 1919. Serial No. 314,717.

To all whom it may concern:

Be it known that I, WILLIAM E. ELLIOTT, a citizen of the United States, residing at Grand Rapids, in the county of Kent and 5 State of Michigan, have invented certain Improvements in Machines for Mounting Articles, of which the following description, in connection with the accompanying drawings, is a specification, like reference characters on the drawings indicating like parts in the several figures.

This invention relates to means for mounting various articles, being directed more particularly to machines for arranging upon a 15 strip buttons and associated securing devices therefor, as staples. In Patent No. 1,147,382, granted July 20, 1915 on my application, is disclosed a package in which a holder, consisting of a flexible strip, has applied to it, 20 at regular intervals, buttons with each of which a securing device is associated, this package being adapted to supply a button-setting machine. Objects of the present invention are to provide for the rapid and 25 economical production of such packages and to insure their uniformity.

As a feature of the invention, I have novel means for bringing into co-operation a holder and articles to be mounted thereon. 30 The holder is usually in strip form, and upon this preferably acts means for preparing it to receive the buttons or other articles, whereupon the article and strip are brought together at the place prepared to effect the 35 mounting. In the machine illustrated there is means for perforating the strip, and preferably also means for bending or corrugating it. These respectively prepare it to receive the button and the securing staple, 40 the former when applied being forced into the perforation, and the latter pressed through the opposite sides of the corrugation.

Another feature of the invention consists in novel means for fixing the mounted article upon the holder. In the present embodiment of the invention this article-fixing means acts a plurality of times, serving both to retain the article during the recession of the article-conveying and pressure means, 45 and to act upon the article to complete its insertion in the holder after its preliminary application. Either of the functions may, however, be performed separately.

To cause uniformity in the application of

the articles, there is also furnished, as a 55 feature of the invention, retaining means for the holder-strip movable into contact with the strip during the preparation of said strip and the application of the article. This retaining means may be operable with strip-preparing means, as with the perforator, 60 they being shown as movable together into contact with the strip, and the retaining means yielding relatively to the perforating means. It is to be observed that the article 65 conveyor and strip feeder also functionate as strip-retaining means at certain stages of the operation.

A further feature provides for the spacing 70 of the articles upon the strip, there being 75 means for advancing the strip after the application of an article to prepare for the application of another article. This advancing means insures the effective feed of the strip by drawing it from the preparing means, it 80 preferably engaging said strip adjacent to the applied articles at a plurality of separated points of simultaneous contact, these being in the present instance at opposite 85 sides of the strip and also spaced from one another in the direction of advance. In the feeding action, the advancing means is moved into and out of engagement with the strip.

Consideration of the following description and claims with the illustrative drawings will make evident other features of the invention. In said drawings,

Fig. 1 is a side elevation of one embodiment of my improved machine, parts being in section;

Figs. 2 to 5, inclusive, show, in sectional elevation, successive positions of the elements of the machine;

Fig. 6 is a vertical sectional detail through the punch and more closely associated parts;

Fig. 7 illustrates the punch in side elevation;

Fig. 8 is an enlarged broken detail, in side 100 elevation, of portions of the strip-corrugating and feeding devices;

Fig. 9 is a detail in end elevation of the strip-corrugating device;

Fig. 10 is a perspective view of the feed- 105 ing slide;

Fig. 11 is a similar view of the button-fixing mechanism;

Fig. 12 is a top plan view of the supporting plate;

Fig. 13 shows, in top plan, the raceway and connected magazine;

Fig. 14 is a partial transverse section on the line 14—14 of Fig. 2;

Fig. 15 is a sectional detail on the line 15—15 of Fig. 13;

Fig. 16 illustrates in perspective the inserting and feeding portions of the pressure member;

Fig. 17 is a top plan view of these parts;

Fig. 18 is a horizontal section on the line 18—18 of Fig. 1;

Figs. 19 to 23, inclusive, are perspective views of the cams and connections for actuating various portions of the machine;

Fig. 24 shows, in perspective, an actuating eccentric for the raceway;

Fig. 25 shows, in side elevation, the package strip with the buttons and staples carried thereby; and

Fig. 26 is a plan view of the strip.

Upon a base 30 is carried a central frame member 32 and a superposed frame member 34, these parts being best shown in Fig. 1 of the drawings. The form of machine illustrated is designed to mount buttons and their securing staples upon a strip of such flexible material as paper. This paper P is taken from a suitable source of supply, as a reel, which is not shown, and passed beneath a perforating punch 36, over a corrugating jaw 38, which respectively prepare the strip to receive the buttons and staples, and is acted upon, adjacent to the punch and jaw, by feeding mechanism which draws the strip step by step from the perforating and corrugating devices to permit them to operate at successive points. Mounted upon the top of rearwardly projecting arms 40 and 42 of the frame section 32 for reciprocation in an inclined direction is a feed slide 44 (Figs. 6 and 10), having at its opposite sides upstanding lugs 46, 46, upon which is fulcrumed a lever 48. The lever includes forwardly extending separated arms 50, 50, which lie at opposite sides of the punch, each arm carrying at its outer extremity a pivoted member 52. These members are provided each with a forward depending projection 54 and a parallel rear projection 56 for engagement with the strip. The projections of the members, by virtue of their pivotal mounting, are self-adjusting upon their pivots to obtain perfect contact of both with the strip, their tilting action being limited by lateral projections 58, which extend into openings in the arms 50. These openings are of sufficient size to allow a restricted movement of the members. Opposite the feeding projections 54, upon the slide 44, are upward projections 60, 60 spaced sufficiently to admit the eye of a but-

ton B, and to the rear of these, beneath the feed projections 56, are horizontally projecting fingers 62, 62. Between the sets of projections 54, 60 and 56, 62 the strip is grasped at opposite sides of the punch and at plural separated points in the direction in which the strip is to be advanced. The former separation leaves ample room for the punch to operate; while the longitudinal spacing provides for the effective non-slipping engagement of the feeding mechanism with the strip. The lever 48 is actuated, to cause the engagement of the projections 54 and 56 with the strip and its release, from a cam 64 secured upon a shaft 66 journaled in bearings 68 of the base 30 (Figs. 1, 18 and 19). The connections between the cam and feed-lever consists of a lever 70 fulcrumed at 69 upon the frame section 32, this lever having an anti-friction roll held against the periphery of the cam by a spring 71 connecting the lever and frame. This spring is one of a similarly arranged series maintaining contact between the various cams and co-operating levers to be hereinafter described. To the lever 70 is articulated a link 72 adjustable in length, if desired, by a right and left nut included in it, the opposite extremity of the link being joined to a lever 74 fulcrumed upon the arm 42 and having separated arms, one of which is connected by a link 76 to the rearwardly extending arm of the lever 48. When the roll of the lever 70 rests upon a circular portion *a* of the edge of the cam, which comprises about three-quarters of its periphery, the jaws are held open. At the end of the portion *a* is an almost radial incline leading to a depression *b*, and, when the anti-friction roll is drawn into this depression by the spring 71, the jaws are closed upon the paper to prepare for its feeding. Finally an opposite incline restores the roll to the peripheral portion *a*. After the closure of the jaws they are moved to advance the strip by a cam 78 upon the shaft 66 (Fig. 20). Upon a lever 80 fulcrumed at 69 adjacent to the lever 70 is a roll contacting with the edge of the cam 78. This lever is connected by an adjustable link 82 to a lever 84 resembling in form the lever 74, and with an arm joined to the lower extremity of the slide 44. The cam 78 has a circular portion *c* merging at each extremity, these points being separated by somewhat more than 180 degrees, into an abrupt projection *d*. During the movement of the edge portion *c* beneath the roll of the lever 80, the slide 44 remains stationary in position while the strip is acted upon by the preparing mechanisms. After the strip-engaging projections have been lowered by the portion *b* of the cam 64, the projection *d* of the cam 78 causes the feed slide to be moved upwardly to advance the

strip the proper amount to receive the succeeding perforation and corrugation. A spring 86 may be interposed between the arm 40 of the frame and an element carried by the feed slide to take up lost motion in the connections.

During the period of rest, the punch 36 acts upon the strip to perforate it for the reception of the eye of a button. The opening produced is preferably in the form of a slit, having a central portion O at the axis of the strip and oppositely diverging end portions o, o. As is best seen in Fig. 26 of the drawings, this perforation forms opposite side side tongues, which enter the button-eye to retain it upon the strip, and opposed end tongues contacting with the outside of the eye to increase the security of its retention. To cut such a perforation, the punch 20 has a central blade 88 with end blades 90 diverging therefrom (Fig. 7). The punch is secured at its upper end to a mounting plate 92 fixed upon the lower extremity of a plunger 94 reciprocating in a bearing 96 carried by the arm 40 of the frame. Surrounding the punch is a strip-retaining pressure sleeve 98 (Fig. 6) movable in an opening in the plate 92 and urged below the punch by a plunger 100, which operates 30 through an opening in the plate 92 and has an enlargement 102 situated in a bore in the punch plunger 94. To force the pressure sleeve downwardly over the punch, a spring 104 is interposed between the enlargement 35 102 of the sleeve plunger and a screw 106 threaded into the upper end of the bore in the plunger 94. The punch and sleeve act against a bed-plate 108, preferably of some relatively soft metal, as brass, supported 40 upon the upper surface of the feed slide 44. The punch and pressure sleeve receive their movement from a cam 110 upon the shaft 66 (Fig. 22), with which cam contacts an anti-friction roll projecting from the side of a lever 112 fulcrumed upon the frame at 69. An adjustable link 114 communicates the movement of the lever 112 to the punch plunger 94, it being connected thereto through lugs 116. tains, as does the magazine tube, lateral grooves 154, 154 to receive the opposite legs of the staples, and an intermediate central groove 156, through which the eyes of the buttons pass, these grooves in the raceway and magazine being alined. Near the lower extremity of the raceway there project into one of the grooves 154 spring fingers 158 and 160 fixed to the top of the raceway and arranged to hold the staples and associated buttons respectively in inserting and feeding positions. Fulcrumed at 162 upon the frame portion 34 (Fig. 1) is a bell-crank lever 164 of triangular plate form, having at its upper angle a pin 166. Pivoted upon this pin is a connecting rod 168, and with opposite sides of the rod contact channel plates 170, 170 fixed upon the adjacent extremities of studs 172 and 174 (Fig. 15). These studs are mounted to turn in openings in separated lugs 176 depending from the raceway, and the plate of the stud 174 is forced into frictional engagement with the connecting rod by a spring 178 interposed between said stud and a screw 180 threaded into the outer end of the bore in which the stud turns. This connection between the bell-crank lever and raceway permits the movement of the former to be communicated to the latter until it is checked by the contact of the lower end of the raceway with the strip overlying the jaws 38, whereupon the rod may slide between the channel plates, permitting a further movement of the lever. To an angle of the lever 164, between its fulcrum point and the pin 166, is connected an eccentric rod 182, preferably adjustable in length, this rod being actuated by an eccentric 185 (Fig. 24) fast upon the shaft 66. Pivoted upon the pin 166 is a pressure and feeding lever 184, acted upon by a spring 186 connecting it with the side of the lever plate to draw a pin 188 projecting laterally from it against the lower edge of a cam-plate 190 fixed to the portion 34 of the frame. At the lower end of the lever 184 are inserting projections 192, 192 (Figs. 16 and 17) separated to permit the passage of the button eye, and the form of which is such as to adapt them for effective engagement with the yokes of the particular form of staple which is to be operated upon. These projections are movable into engagement with a staple held at the bottom of the raceway by the spring 158. Between the projections 192, 192 and the fulcrum of the lever 184 are similarly separated feeding projections 194, 194, which engage the staple held by the spring 160 to carry it forward to the inserting position under the influence of the spring 158, when the staple at the latter position is moved forward by the projections 192. A projection 196 of the plate 190, when in contact with the pin 188, holds both pairs of projections 192 and 194 out of engagement with the staples. As the lever 184 is advanced by the movement of the actuating lever 164, the pin 188 moves from the projection on to a narrower portion 198 of the cam-plate to bring the inserting and feeding projections against the yokes of the first and second staples of the series supported in the raceway. Upon the movement of the lever in the opposite direction, a pivoted finger 200 engages the pin 188 and, swinging with it as it travels upwardly, lowers the projections 192 and 194 below the line of the staples to prevent interference with them during this idle movement. It will be seen that when the lever 164 first moves to the right, as viewed in Fig. 1, the raceway and lever 184 are both lowered. This continues until the travel of the raceway is stopped by the jaw 38. This contact aids in the formation of the corrugation and temporarily clamps the strip. The connecting rod 168 now slips through the frictionally engaging channel plates 170, allowing the continued advance of the lever 184. The projections 192 take the staple from the spring 158 and thrust it through the corrugation formed by the jaw, at the same time carrying the button eye partially into the perforation produced by the punch 36, the button at this time being supported by the plate extension 124. Simultaneously with this, the lever projections 194 are bringing the succeeding staple and its button from the spring 160 to the inserting position. The retreat of the raceway and pressure lever leaves the lowermost staple inserted through the strip and the button seated upon the supporting fork, with newly advanced staples and buttons positioned by the springs 158 and 160.

Carried by the feed slide 44 and co-operating with the heads of the buttons during their application to the strip is a fixing device, performing the double function of retaining them against displacement during the withdrawal of the raceway and inserting projections, and applying a second pressure to seat the button eyes in their slits after the primary insertion. Surrounding the feed slide 44 just at the rear of the lugs 46 is a bracket 202 (Figs. 1 and 11), secured in place by a strap 204 extending across the top of the slide screwed to the opposite sides of the bracket. From this bracket rise lugs, upon which is fulcrumed a lever 206, with the forward end extending over the fork 124, and having at its under side a depression 208 of such contour as to fit over the head of a button. Pivoted to the rear or lower end of the lever is a link 210 joined at its opposite extremity to a lever 212 fulcrumed on the frame arm 40. A link 214 joins this lever to a second lever 216 mounted to rock with the other cam-levers about the fulcrum 125

69, and having an anti-friction roll resting against the periphery of a cam 218 secured upon the shaft 66. A circular portion p of the cam maintains the button-engaging 5 end of the lever 206 raised. Beyond this circular portion p , which includes over 180 degrees of the circumference of the cam, is a depression q . When the roll of the lever 216 enters this depression, the lever 206 is 10 brought into contact with the button resting upon the fork 124, and holds it during the recession of the raceway and pressure lever to prevent its displacement. As the strip and applied button and staple are advanced 15 for the production of the succeeding perforation and corrugation, a projecting portion r of the cam 218 moves the engaging depression 208 of the lever 206 out of contact with the button, and shortly after this 20 a depression s , similar to q , reaches the lever roll and the engaging end of the lever 206 is again brought quickly against the head of the button. At this time it is freed from the fork 124, and the blow acts to 25 finally seat the eye in the slit.

The successive stages in the operation of the machine are well illustrated by Figs. 1 to 5 of the drawings. Fig. 1 may be considered to show the apparatus in substantially its normal position, although the raceway and pressure lever have started upon their downward stroke. The elements acting upon the strip and buttons and staples are at rest and, save that the pressure 30 sleeve is lowered, are out of contact with these articles. The machine is supplied with a magazine tube, and it will be assumed that at least one operation has been performed, so that a button and staple are held by the raceway spring 158, and a perforation has been made in the strip, but has not received a button. As the cam-shaft 35 is rotated by power applied in any suitable way, as a belt passing over a pulley 220 fixed upon it, the parts attain the positions shown in Fig. 2. Here the eccentric 40 185 has moved the raceway down in preparation for the delivery of the lowermost button to the supporting fork 124. The pressure sleeve 98 is maintained against the strip to fix it upon its supporting plate 45 108, and the edge of the punch 36 is by the cam 110 immediately thereafter forced through the strip to produce the next 50 perforation O , o . Simultaneously the jaw 38 is moved up by the cam 184 and coacts with the plate 122 and the end of the raceway to form a corrugation in the strip adjacent to the perforation previously made 55 by the punch. Referring now to Fig. 3, which represents the elements upon a further rotation of the cam-shaft, the continued 60 movement of the eccentric brings down the pressure lever 184 to remove the end staple from the spring 158 and force it through

the opposite sides of the corrugation, and effects the preliminary or partial introduction of the button eye into the slit. The punch is at this time partly retracted by the cam 110, but the pressure sleeve remains down to clamp the strip in position. As illustrated in Fig. 4, the lever 206 has brought the depression 208 into its first contact with the head of the button, holding it while the pressure lever and raceway are 70 retracted. The punch is now fully raised, and the pressure sleeve continues in contact with the strip. Approaching the completion of the cycle of operations, as illustrated in Fig. 5, the upward movement of 75 the pressure lever and raceway continues, the feeding projections are brought against the strip by the cam 64, and the feed slide advanced by the cam 78, moving the strip forward a distance equal to that between 80 succeeding perforations. During this travel, while the strip is held between the projections 54 and 60, the end of the lever 206 taps the head of the button under the influence of the cam 218 to complete its seating in the slit. Finally the lever 206 is 85 raised, the projections 54 and 56 are lifted out of contact with the strip, and the feed slide 44 returned to its lowest position, bringing, with the further upward movement of the raceway and pressure lever, 90 the elements to their initial relation.

Having described my invention, what I claim as new and desire to secure by Letters Patent of the United States is:

1. In a machine for mounting articles upon a strip, means for perforating the strip to receive and temporarily hold an article by engagement of the strip therewith, and means for bringing together the article and strip with said article in the perforation.

2. In a machine for mounting a plurality of assembled articles upon a strip, independent means for preparing the strip to receive each of a plurality of the assembled articles, and means for applying the articles at the places prepared.

3. In a machine for mounting a plurality of assembled articles upon a strip, independent means for preparing the strip to receive each of a plurality of the assembled articles, and plural means for applying the articles at the places prepared.

4. In a machine for mounting a plurality of assembled articles upon a strip, means for preparing the strip to receive each of a plurality of the assembled articles, plural means for applying the articles at the places prepared, and means for imparting to said plural means different article-applying movements.

5. In a machine for mounting buttons upon a holder, means for forming the holder to receive a button, and means for bringing

- ing into co-operation a button and the holder, said means being constructed and arranged to effect the retention of the button by its engagement with the holder at the point formed for its reception.
6. In a machine for mounting buttons and their securing devices upon a holder, means for bringing into co-operation a button and the holder, and means for bringing into co-operation a securing device and the holder, said means being constructed and arranged to effect the retention of the button by the holder independently of the securing device.
- 15 7. In a machine for mounting buttons and their securing devices upon a holder, means for forcing a button through the holder, and means for forcing the securing device through said holder.
- 10 8. In a machine for mounting buttons and their securing devices upon a holder, means for perforating the holder to receive a button, and means for forcing a button into the perforation.
- 15 9. In a machine for mounting buttons and their securing devices upon a holder, a member movable into contact with the holder and acting independently of the buttons to bend the holder, and means for forcing a securing device through the bent portion.
- 20 10. In a machine for mounting buttons and their securing devices upon a holder, means for perforating the holder to receive a button, means for bending the holder, means for forcing a button into a perforation, and means for forcing a securing device through the bent portion.
- 25 11. In a machine for mounting buttons and their securing devices upon a holder, means for corrugating the holder, and means arranged to force a securing device through opposite sides of the corrugation at the same side of the holder as the button head.
- 30 12. In a machine for mounting articles upon a perforated holder, conveying means traveling with an article for bringing it into preliminary association with the holder perforation, and means acting thereafter upon an article independently of the conveying means to seat it in the holder perforation.
- 35 13. In a machine for mounting a series of articles upon a holder, means for successively bringing together the articles and holder, and means acting a plurality of times upon each article and at different points in its advance to fix it upon the holder.
- 40 14. In a machine for mounting articles upon a holder, a support, means for engaging an article, said means being movable toward the support to produce the retention of the article by the holder and also being movable from the support, and means movable for contact with the article during the movement of the engaging means from the support.
- 45 15. In a machine for mounting articles upon a holder, a support, article-applying means movable toward and from the support and arranged to insert an article in the holder, and means movable independently of the applying means and contacting with the article during the movement of the applying means from the support.
- 50 16. In a machine for mounting articles upon a holder, means for moving the holder, a support, means arranged to insert an article in the holder and movable toward and from the support, and means movable with the holder and contacting with an article after such insertion and during the movement of the inserting means from the support.
- 55 17. In a machine for mounting articles upon a holder, a support, means movable toward and from the support and arranged to convey assembled articles and apply them together to the holder, and retaining means contacting with an applied article during the movement of the conveying and applying means from the support.
- 60 18. In a machine for mounting articles upon a holder, a support, article-conveying means movable toward and from the support, an article-engaging member, means for moving the engaging member into contact with an article during the movement of the conveying means from the support, and means for thereafter moving the engaging member into contact with the article.
- 65 19. In a machine for mounting articles upon a holder, means for applying an article to the holder, means for grasping the holder, and means movable into successive engagement with an article upon the holder during the operation of the applying means and the grasping means.
- 70 20. In a machine for mounting articles upon a holder, means for inserting an article in the holder, advancing means movable into engagement with the holder, and means traveling with the holder and engaging an article upon said holder during the engagement of the holder by the advancing means.
- 75 21. In a machine for mounting buttons upon a strip, means contacting with a button to effect its preliminary insertion in the strip, and means acting to complete the insertion of the button.
- 80 22. In a machine for mounting buttons and their securing devices upon a strip, means for applying a securing device and thereafter a button to the strip, and means engaging the button after said application.
- 85 23. In a machine for mounting buttons and their securing devices upon a strip, means for applying a button and securing device to the strip, and means engaging the button a plurality of times after said application.
- 90 24. In a machine for mounting buttons

- and their securing devices upon a strip, movable means for applying a button and securing device to the strip, button-engaging means, and means for moving the engaging means into and out of contact with the button both during and after the movement of the applying means. 65
25. In a machine for mounting buttons upon a strip, means for forming an opening in the strip, means for partially inserting a button in the opening, and means for further inserting the button in the opening. 70
26. In a machine for mounting buttons upon a flexible strip, a punch operating upon the strip, and a pressure member for inserting a button into the opening produced by the punch. 75
27. In a machine for mounting buttons upon a flexible strip, a punch operating upon the strip, and a pressure member contacting with a button to force it into the strip. 80
28. In a machine for mounting assembled buttons and staples upon a flexible strip, a corrugating member for engagement with the strip, and a member engaging a staple for forcing it through the corrugation and acting to carry the associated button into engagement with the strip. 85
29. In a machine for mounting buttons and staples upon a flexible strip, a punch operating upon the strip, a corrugating member for engagement with the strip, and a member engaging a staple for forcing it through the corrugation and inserting a button eye into the opening produced by the punch. 90
30. In a machine for mounting buttons and staples upon a flexible strip, a punch operating upon the strip, a corrugating member for engagement with the strip, a member engaging a staple for forcing it through the corrugation and inserting a button eye in the opening produced by the punch, and a member engaging the button head to complete the introduction of the eye of the button into the opening produced by the punch. 95
31. In a machine for mounting buttons and staples upon a flexible strip, a punch operating upon the strip, a pressure member for inserting buttons in the openings produced by the punch, a member for contact with the heads of the buttons, and means for moving the member a plurality of times into contact with each button head. 100
32. In a machine for mounting buttons and staples upon a flexible strip, a punch operating upon the strip, a reciprocating pressure member for inserting a button in the opening produced by the punch, a member for contact with the head of a button, and means for moving the member into contact with the head of a button during the movement of the pressure member in one direction and for thereafter again effecting contact with said button head. 105
33. In a machine for mounting buttons and staples upon a flexible strip, a reciprocating button and staple conveyor, a reciprocating pressure member for forcing a button and staple from the conveyor into co-operation with the strip, and a member for contact with the head of the button during the movement of the conveyor and pressure member from the strip. 110
34. In a machine for mounting buttons and staples upon a flexible strip, a punch operating upon the strip, a pressure member for inserting a button into the opening produced by the punch, a feeder for the strip, and a member contacting with the head of the button during the feeding operation to seat it in the opening. 115
35. In a machine for mounting buttons and staples upon a flexible strip, a punch operating upon the strip, a pressure member for inserting a button into the opening produced by the punch, a feeder for the strip, and a member for contact with the head of the button, said member being movable with the feeder. 120
36. In a machine for mounting articles upon a strip, means for perforating the strip to receive an article, retaining means contacting with the strip during its perforation, and means for bringing together the article and strip. 125
37. In a machine for mounting articles upon a strip, means for preparing the strip to receive an article, means for bringing together the article and strip at the place prepared, and retaining means movable in advance of the preparing means into contact with the strip during the application of the article. 130
38. In a machine for mounting articles upon a strip, means for corrugating the strip to receive an article, and means for applying the article to the corrugation and including a raceway contacting with the strip during such application. 135
39. In a machine for mounting articles upon a strip, a plurality of means operating upon the strip to prepare it to receive an article, means for bringing together the article and strip at the place prepared, and retaining means movable into contact with the strip and operable with each of the preparing means. 140
40. In a machine for mounting a plurality of assembled articles upon a strip, independent means for preparing the strip to receive each of a plurality of the assembled articles, means for applying the articles at the places prepared, and means movable with one of the preparing means for retaining the strip in position. 145
41. In a machine for mounting buttons

and their securing devices upon a holder, means for forcing into co-operation a button with its associated securing device and the holder, and retaining means movable into contact with the holder and acting during the forcing operation.

42. In a machine for mounting buttons and their securing devices upon a holder, means for forcing into co-operation a button with its associated securing device and the holder, and article-conveying means movable into contact with the holder and acting during the forcing operation.

43. In a machine for mounting buttons and their securing devices upon a holder, means for perforating the holder to receive a button, means for forcing a button into the perforation, and retaining means for the holder movable with the perforating means.

44. In a machine for mounting buttons and their securing devices upon a holder, means for perforating the holder to receive a button, means for forcing a button into the perforation, and retaining means for the holder movable with the perforating means and being yieldable independently thereof.

45. In a machine for mounting buttons and staples upon a flexible strip, a punch operating upon the strip, a pressure member for inserting a button into the opening produced by the punch, and a retaining member contacting with the strip during the operation of the pressure member.

46. In a machine for mounting buttons upon a flexible strip, a punch operating upon the strip, a pressure member for inserting a button into the opening produced by the punch, and a retaining member for the strip operating with the punch.

47. In a machine for mounting buttons upon a flexible strip, a punch operating upon the strip, a yieldable strip retaining member movable with the punch, and a pressure member for inserting a button into the opening produced by the punch.

48. In a machine for mounting buttons upon a flexible strip, a punch operating upon the strip, a yieldable member surrounding and extending normally beyond the punch, and a pressure member for inserting a button into the opening produced by the punch.

49. In a machine for mounting articles upon a strip, means for preparing the strip to receive an article, means for bringing together the article and strip at the place prepared, and means movable into and out of engagement with the strip at a plurality of points separated in the direction of advance for advancing said strip.

50. In a machine for mounting articles upon a strip, means for preparing the

strip to receive an article, means for bringing together the article and strip at the place prepared, and means movable into and out of engagement with the strip at opposite sides and at points separated in the direction of advance for advancing said strip in preparation for the application of another article.

51. In a machine for mounting buttons upon a flexible strip, a punch operating upon the strip, a pressure member for inserting a button into the opening produced by the punch, and a feeder contacting with the strip between the punch and pressure member.

52. In a machine for mounting buttons upon a flexible strip, a punch operating upon the strip, a pressure member for inserting a button into the opening produced by the punch, and a feeder contacting with the strip at opposite sides of the punch.

53. In a machine for mounting buttons upon a flexible strip, a punch operating upon the strip, a pressure member for inserting a button into the opening produced by the punch, and a feeder contacting with the strip at opposite sides of the punch and at points separated in the direction of feed.

54. In a machine for mounting buttons and staples upon a flexible strip, means for holding the strip for the application of a button and staple, means for applying said button and staple to the strip, movable engaging means acting upon opposite faces of the strip, and means for moving said engaging means to feed the strip.

55. In a machine for mounting buttons and staples upon a flexible strip, means for holding the strip for the application of a button and staple, means for applying said button and staple to the strip, and feeding means arranged to engage opposite faces of the strip.

56. In a machine for mounting buttons and staples upon a flexible strip, means for holding the strip for the application of a button and staple, means for applying said button and staple to the strip, and a feeding lever having members engaging the strip at opposite sides of the point of application, said members being pivoted upon the lever between their points of engagement with the strip.

57. In a machine for mounting buttons and staples upon a flexible strip, means for holding the strip for the application of a button and staple, means for applying said button and staple to the strip, and a feeding lever having members engaging the strip at opposite sides of the point of application and at separated points longitudinally of the strip, said members being pivoted upon the lever between said separated points.

58. In a machine for mounting articles

upon a strip, means for preparing the strip to receive an article, means for bringing together the article and strip at the place prepared, means engaging the strip adjacent to the applied article for advancing said strip, and means contacting with the article during the engagement of the advancing means to assist in the application.

59. In a machine for mounting assembled articles upon a holder, a support, means for bringing the articles and the holder into proximity with the support, and means co-operating with the support and arranged to apply the articles to the holder for ready detachment and utilization as assembled.

60. In a machine for mounting articles upon a holder, a support, means for bringing the articles and the holder to opposite sides of the support, and means for forcing 20 the articles from the support and through the holder.

61. In a machine for mounting upon a holder a plurality of assembled articles, a support, means for advancing the holder beneath the support, and means for bringing one of the assembled articles upon the support and another of said articles beneath the support and forcing it through the holder.

62. In a machine for mounting articles upon a holder, a support upon which an article rests during the mounting operation, means for advancing the holder into proximity with the support, means co-operating with the support to form the holder, and means co-operating with the support for applying an article to the formed portion of the holder.

63. In a machine for mounting articles upon a holder, a holder-support, an article-support, perforating means co-operating with the holder-support, and means for forcing articles from their support and through the holder while maintaining them in condition for utilization upon removal 45 from the holder.

64. In a machine for mounting a plurality of assembled articles upon a holder, a support upon which one of the assembled articles rests during the mounting operation, means for advancing the holder into proximity with the support, means co-operating with the support to corrugate the holder, and means arranged to cause another than the supported article to perforate the walls 55 of the corrugation.

65. In a machine for mounting articles upon a holder, an article support, means for advancing the holder into proximity with the support, means co-operating with the support to corrugate the holder, retaining means co-operating with the corrugating means, and means for forcing an article through the corrugation.

66. In a machine for mounting articles upon a holder, a holder-support, a support

for each of a pair of assembled articles, means for forcing the supported articles in their assembled condition through the holder, and retaining means co-operating with the holder-support during the forcing operation.

67. In a machine for mounting articles upon a holder, a support, means for advancing the holder into proximity with the support, means co-operating with the support to corrugate the holder, means for forcing an article through the corrugation, and article-conveying means co-operating with the corrugating means to form the holder.

68. In a machine for mounting articles upon a holder, a support, article-conveying means delivering to the support, means for advancing the holder in proximity with the support, and unitary means co-operating with the support for forcing an article from the conveying means to the support and through the holder.

69. In a machine for mounting articles upon a holder, a support, article-conveying means delivering to the support, means for advancing the holder in proximity with the support, means co-operating with the support for forcing an article from the conveying means to the support and through the holder, and retaining means co-operating with the articles upon the support.

70. In a machine for mounting articles upon a holder, a support, means co-operating with the support for applying an article to the holder, means for advancing the holder with an applied article, and means movable into contact with an article during its advance to force it toward the holder.

71. In a machine for mounting buttons upon a strip, a support, a conveyor for bringing buttons into proximity with the support, means for perforating the strip, means for feeding the perforated strip across the support, and means co-operating with the support for forcing a button portion through the strip perforations.

72. In a machine for mounting upon a strip buttons and securing devices assembled therewith, a support, means for feeding the strip beneath the support, and unitary means for bringing upon the support a button with its securing device and forcing said securing device through the strip.

73. In a machine for mounting buttons and their associated securing devices upon a strip, a support, means for feeding the strip across the support, means for forcing the strip against the support to form it, and means for applying a button and its securing device to the formed portion.

74. In a machine for mounting buttons upon a strip, a strip-support, a button-support, strip-perforating means co-operating with the strip-support, and means for forc-

ing a button from its support through a perforation.

75. In a machine for mounting buttons upon a strip, a strip-support, a button-support, strip-perforating means co-operating with the strip-support, means for forcing a button from its support through a perforation, and retaining means movable into contact with the strip during the forcing operation.

76. In a machine for mounting buttons upon a strip, a strip-support, a button-support, strip-perforating means co-operating with the strip-support, means for forcing a button from its support through a perforation, and button-conveying means delivering to the support and movable into contact with the strip during the forcing operation.

77. In a machine for mounting buttons and assembled securing devices upon a strip, a support, button-conveying means delivering to the support, means for advancing the strip into proximity with the support, and means contacting with a securing device for forcing it with its button from the conveying means to the support and through the strip.

78. In a machine for mounting buttons and assembled securing devices upon a strip, a support, button-conveying means delivering to the support, means for advancing the strip into proximity with the support, means contacting with a securing device for forcing it with its button from the conveying means to the support and through the strip, and retaining means contacting with the button upon the support.

79. In a machine for mounting buttons upon a strip, a support, means co-operating with the support for applying buttons to the strip, means for feeding the strip with the applied buttons, and oscillatory means

for forcing the buttons toward the strip during the advance.

80. In a machine for mounting buttons and staples upon a flexible strip, a button and staple raceway, a plate, a strip-engaging jaw co-operating with the plate, and a pressure member for forcing a staple with a button from the raceway and through the strip held between the jaw and plate.

81. In a machine for mounting buttons and staples upon a flexible strip, a button and staple raceway, a plate, a strip-corrugating jaw co-operating with the plate, and a pressure member for forcing a staple with a button from the raceway and through the corrugation produced by the jaw.

82. In a machine for mounting buttons and staples upon a flexible strip, a button and staple raceway, a plate, a strip-corrugating jaw co-operating with the plate and raceway, and a pressure member for forcing a staple with a button from the raceway and through the corrugation produced by the jaw.

83. In a machine for mounting buttons and staples upon a flexible strip, a button and staple raceway, a plate having a button-supporting extension, a strip-engaging jaw co-operating with the plate, and a pressure member co-operating with the raceway for forcing a staple through the strip held between the jaw and plate and the associated button upon the support extension.

84. In a machine for mounting buttons and staples upon a flexible strip, a strip-feeding slide having a punch block, a punch co-operating with the block to perforate the strip, and means for inserting buttons in the strip perforations.

In testimony whereof I have signed my name to this specification.

WILLIAM E. ELLIOTT.
